Primary Examiner — Elizabeth J Oswecki*(74) Attorney, Agent, or Firm* — Faegre Baker Daniels LLP(57) **CLAIM**

The ornamental design for mouthguard, as shown and described.

DESCRIPTION

FIG. 1 is a front perspective view of a mouthguard, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

Features shown in dashed lines form no part of the claimed design.

1 Claim, 8 Drawing Sheets# US D839,485 S
